(57) **CLAIM**

The ornamental design for an dock for an electronic device, as shown and described.

DESCRIPTION

FIG. 1 is a perspective view showing our new dock for an electronic device design;

FIG. 2 is a side view thereof;

FIG. 3 is a top view thereof;

FIG. 4 is a front view thereof;

FIG. 5 is another side view thereof;

FIG. 6 is a back view thereof; and,

FIG. 7 is a bottom view thereof.

The broken lines represent the portions of the design that form no part of the claim.
